UNITED STATES PATENT OFFICE.

FREDERICK McDONALD, OF ALBANY, NEW YORK, ASSIGNOR TO AMERICAN METER COMPANY, INCORPORATED, OF NEW YORK, N. Y., A CORPORATION OF DELAWARE.

DIAPHRAGM FOR GAS METERS.

Application filed June 9, 1923. Serial No. 644,513.

The present invention relates to an improvement in diaphragms for gas meters and more particularly to the construction of the membrane portion thereof which is commonly referred to in the art as the "diaphragm leather". At the present time and, so far as applicant is informed, for many years past, diaphragms for some types of gas meters have included as elements of their construction two or more spaced frame members to which is secured a suitable membrane or membrane-like member of flexible material such as tanned lamb skin, this being the particular material which has been found most satisfactory in use over a period of many years. Manufacturing conditions make it practically essential that these leathers be made up of two or more separate pieces having their ends sewed and cemented together in overlapping relation to prevent leakage at the joints. Leakage through the pore openings of the lamb hide or skin is commonly overcome by the use of pore filling liquids such as certain kinds of oils well known in the art. This, however, does not entirely eliminate leakage in the vicinity of the overlapping portions of seams even where the pieces are cemented together by shellac and then sewed in the most effective manner.

A long series of tests has revealed the fact that somewhere between twelve and fifteen per cent of all seams thus cemented and sewed will produce at least one small puncture which is, of course, sufficient to render the membrane defective. This means that the defective seams must be cut out of the material and new membranes made from the salvaged pieces, resulting not only in a waste of material, but also in a greater waste of time and labor. Heretofore it has been customary, in the manufacture of diaphragms, to secure the leather to the frames with the hair surface or side exteriorly exposed and the opposite or flesh side interiorly exposed, or vice versa, so that, in securing component pieces together a portion of the flesh side of one piece is in contact with and secured to a portion of the hair side of the other piece.

When these pieces are sewed together by felling stitches the needle passes through

both sides of one piece but through only one side of the opposed piece. In practice, it happens that the needle either punctures the second side of said opposed piece or makes an opening which communicates with a pore in said piece, thus producing a leak. I have discovered that the number of openings or leaks produced in sewing can be materially reduced if the parts to be sewed together are arranged with the flesh side of one piece engaging the flesh side of the other. With this arrangement the needle pierces both sides of one piece as heretofore but does not penetrate the hair side of the opposed or contiguous piece. Very extensive tests of diaphragms having the pieces sewed together in this manner indicate only four tenths per cent of defective seams. While the beneficial results of sewing the pieces together with the flesh side of one piece contiguous with the flesh side of the other piece are very marked, the reasons therefor are as yet obscure. One theory in explanation of the phenomenon is that the layer exposing the hair side of the skin is of closer texture than that exposing the flesh side, and that in any given skin the cross sectional layer or increment of close or relatively impervious texture is substantially thinner than the remaining layer or increment exposing on the flesh side. Thus, a needle penetrating the relatively thin impervious layer may frequently make an opening which communicates with the relatively porous layer without passing entirely through said layer, thus forming a minute passageway causing leakage at that point. However, leakage is less likely along a seam in which the needle passes through only one increment of close texture rather than through the close texture layers of both pieces as is the case in the present practice. So much for my invention in so far as it relates to the prevention of initial leaks or perforations in the diaphragm membrane.

Long experience in the gas meter art indicates that leaks frequently develop in use along the seams of the diaphragm apparently by reason of the stiffening or hardening of the shellac which causes the leather to crack when flexed. The choice of adhesives is limited considerably by the char-

acter of the gases encountered in the meters and other conditions and it has therefore been necessary to accept the lesser evil of eventual hardening and cracking as compared with the greater evil of chemical or other reaction between the gas and the adhesive which would result in a much speedier deterioration of the diaphragm. I have discovered that a solution of nitrocellulose and amyl acetate when applied to the joint between the pieces of skin making up the diaphragm leather produces an effective and seemingly permanent bond unaffected by conditions ordinarily encountered in the use 10 of gas meters. This adhesive, besides being unaffected by the ingredients of the gas, appears to retain its flexibility to such an extent that cracking of the leather in operation of the diaphragm is reduced to a minimum, thus more fully meeting the requirements of practical conditions of operation by extending the period of effective use of the device. Furthermore, I have also found that the employment of the nitrocellulose 15 adhesive, particularly where the pieces of leather are joined flesh side to flesh side, gives the resulting membrane a composite tensile strength materially greater than that of membranes including shellac cemented joints. Extensive tests with a commonly used grade of lamb skin indicate that the shellac joint separates at about seventy pounds pull, whereas the nitrocellulose cemented joint is at least as resistant to breaking 20 under pulling pressure as the material itself, thus indicating that the character of the bond between the pieces of leather when made by means of nitrocellulose is materially different from the character of the bond formed when shellac is used. It is contemplated that under some circumstances the use of the nitrocellulose cement may render sewing of the joint unnecessary. This 25 has never been possible in the gas meter art where shellac or other known adhesives have been used on account of the relatively insecure character of the joint and the tendency of the shellac to cause cracking of the leather, for that reason rendering necessary 30 a supplementary fastening expedient in the form of sewing. Obviously, the combination of the nitrocellulose cement and the sewing without penetration of both increments of hair side produces a peculiarly effective joint or seam for the particular use indicated.

My invention will be better understood by reference to the drawings illustrating one

embodiment thereof, which form a part of the present specification, and in which— 60

Figure 1 is a view in perspective of a gas meter diaphragm, and

Figure 2, a section on the line 2—2 of Figure 1.

The drawings disclose a diaphragm construction including spaced supports or frames 1 and 2 to which is secured a membrane made up of two separate pieces of lamb skin 3 and 4, the peripheral edges of said pieces being fastened to the frames by 65 means of windings 5 and 6, respectively. As indicated more clearly in Figure 2, the separate pieces 3 and 4 have their end portions 70 mutually overlapping with the flesh side 7 of the piece 4 opposed to the flesh side 8 of the piece 3, said opposed portions being held 75 together by a suitable adhesive 9, preferably a solution of nitrocellulose and amyl acetate. The joint thus formed is made more secure 80 by means of rows of stitching including 85 stitches 10, said stitches avoiding penetration of both increments of hair side 11 and 12 along any given line of stitching. Although I have shown the seams or joints with the stitch reinforcement, it is contemplated 90 that under some circumstances, this reinforcement may be dispensed with on account of the effective bond afforded by the particular preferred adhesive hereinabove referred to.

The illustrated embodiment of my invention shows the use of two separate pieces of skin. It will be obvious that a similar result may be accomplished by using a greater number of pieces, for example, four or six, 95 the essential feature so far as the number of pieces is concerned, being to provide an even number so that it may be possible at every joint to have the flesh side of one end portion opposed to the flesh side of the next 100 adjacent end portion.

I claim as my invention:

A membrane for gas meter diaphragms comprising a plurality of pieces of leather arranged with end portions of the flesh side 105 surface of one piece overlapping and adhesively secured to end portions of the flesh side surface of the adjacent piece, each piece having a series of felling stitches passing therethrough and engaging a contiguous 110 portion of said adjacent piece without passing through the hair side thereof.

In testimony whereof, I have signed my name to this specification this 7th day of June, 1923.

FREDERICK McDONALD.
